UNITED STATES PATENT OFFICE.

SHIRL HERR, OF CRAWFORDSVILLE, INDIANA.

HIDDEN-METAL DETECTOR.

Application filed February 4, 1924. Serial No. 690,360.

My invention consists of an improvement in hidden metal detectors, and the primary object of the invention is to provide portable means of locating submerged, buried or hidden metallic objects by the production of sound waves effected through distortion of a magnetic field by reason of the object coming within the field. A further object of my invention resides in the simplicity 10 of its construction such that the device is effective with a single primary winding and a single secondary winding. I accomplish these and such other objects as may hereinafter appear by the means shown 15 more or less diagrammatically in the accompanying drawing, in which

Fig. 1 is a plan view of the detector illustrating the wiring diagram and the relation of the primary and secondary windings; Fig. 2, a vertical section taken on the line 2—2 of Fig. 1; and Fig. 3, a vertical section taken on the line 3—3 of Fig. 1.

Like characters of reference indicate like parts throughout the several views. 25 About an iron pole-piece 5, I wind the primary winding 6 which has one terminal connected by the wire 7 to a storage battery 8. The wire 9 leading from the other terminal of the primary winding 6 is connected to an automatic contact breaker of usual and well known construction, comprising the armature core 10, about which the wire 9 is wound, the vibrating spring member 11 having the contact point 12 in circuit with the wire 9 leading from the core 10, and the stationary point 13 adapted to be contacted normally by the point 12. The stationary point 13 is in turn connected to the other terminal of the storage battery 8 35 by the wire 14. With the circuit completed as above described, the points 12 and 13 will rapidly break and make contact such that the current flowing through the primary winding 6 is of pulsating nature, which 40 sets up a corresponding magnetic field about the winding 6 and its pole-piece 5.

The pole-piece 5 is supported by the ties 15 bearing on the cross members 16 carried by the frame 17 of non-metallic material such as wood, about which is wrapped the secondary winding 18, so held at an appreciable distance from the pole-piece 5 and its winding 6. The two terminals of the secondary winding 18 are connected to a telephone receiver 19 of usual and well known construction. The pole-

piece 5 is provided with the slots 20 to receive the ties 15 and the top wedges 21 and 22 and the under wedges 23 and 24.

My detector requires an initial adjustment 60 of the wedges 21, 22, 23, and 24 such that the pole-piece 5 and its winding 6 may be so located within the secondary winding, and there secured that no sound is heard from the receiver 19. With the use of 65 wedges the pole-piece may be tilted, moved up or down, or horizontally to obtain the proper location in respect to the secondary winding 18. When the detector is carried about in an attempt to locate the object 70 sought, the receiver 19 is held to the observer's ear, and no sound is heard until a metallic object is brought within range of the magnetic field set up by the primary winding 6, when the presence of such an 75 object will so disturb the magnetic field as to permit the induced current in the secondary winding 18 to cause the telephone receiver 19 to emit a distinct sound.

The range within which the detector must 80 be brought to the object sought, I find to be from four to six feet with my present construction, but this may be varied by varying the current and the relation and proportion of primary and secondary windings. 85

Having fully described my invention in the form now best known to me, I desire to set forth that the structure is capable of variations without departing from the spirit of the invention, and I therefore do not desire to be limited to the precise form as shown, nor any more than may be required by the following claims.

I claim:

1. In a metal detector, the combination 95 with a source of electric current, an automatic vibrating contact breaker, and a telephone receiver, of a pole-piece, a primary winding on said pole-piece in electrical circuit with said source of electric current and 100 said contact breaker, a frame supporting said pole-piece, and a secondary winding wound about the periphery of said frame, said secondary winding being at right angles to and being at a substantial distance 105 from said primary winding and being in electrical circuit with said telephone receiver.

2. In a metal detector, the combination 110 with a source of electric current, an automatic contact breaker, and a telephone receiver, a pole-piece, a primary winding on said pole-piece in electrical circuit with said

source of current and said contact breaker, a non-metallic frame centrally supporting said pole-piece, and a secondary winding surrounding said primary winding mounted 5 on the said frame at a substantial distance from said primary winding and such that the axis of the secondary winding is normal to the axis of the primary winding magnetic field, and electrical conductors placing said 10 telephone in electrical circuit with the secondary winding.

3. In a metal detector, the combination with a source of electric current, an automatic vibrating contact breaker, and a telephone receiver, of a pole-piece, a primary winding on said pole-piece in electrical circuit with said source of current and said contact breaker, a frame supporting said pole-piece, a secondary winding wound about 15 the periphery of said frame, said secondary winding being at right angles to and being at a substantial distance from said primary winding and being in electrical circuit with said telephone receiver, and means of adjustingly securing said pole-piece in said 20 25

frame centrally of said secondary winding.

4. In a metal detector, the combination with a source of electric current, an automatic contact breaker, and a telephone receiver, of a pole-piece, a primary winding on 30 said pole-piece, conductors placing said primary winding in circuit with said source of current and said contact breaker, a frame supporting said pole-piece, cross members in said frame, ties between said cross members, a plurality of wedges on and under said ties engaging with said pole-piece, a secondary winding surrounding said primary winding mounted on said frame, said secondary winding being at a substantial 35 distance from said primary winding and being normal to the primary winding, and electrical conductors placing said telephone receiver in circuit with said secondary winding. 40 45

Signed at Crawfordsville, in the county of Montgomery and State of Indiana, this 1st day of February, 1924.

SHIRL HERR.
